UNITED STATES PATENT OFFICE.

MARTIN J. SCHMITT, OF NEW YORK, N. Y., ASSIGNOR OF ONE-HALF TO CHARLES J. HETTESHEIMER, OF BROOKLYN, NEW YORK.

DESIGN FOR A REEL AND INCLOSING SUPPORT.

49,284.

Specification for Design.

Patented June 27, 1916.

Application filed September 27, 1915. Serial No. 52,968. Term of patent 3½ years.

To all whom it may concern:

Be it known that I, MARTIN J. SCHMITT, a citizen of the United States of America, residing at the borough of Brooklyn of the city of New York, in the county of Kings and State of New York, have invented a new, original, and ornamental Design for a Reel and Inclosing Support, of which the following is a specification, reference being had to the accompanying drawing, forming part hereof.

Figure 1 is an elevation of a reel and inclosing support showing my new design; and Fig. 2 is a side view of the same.

In the drawing A represents the inclosing support for the reel, constructed in ornamental form and having a central open portion B to contain the reel C having a handle D.

The lower part of the body portion of the support A has an interiorly disposed stepped opening indicated by dotted lines,

and the upper portion of the said support terminates in an exterior stepped portion or extension, the said stepped portions serving as means of attachment of the structure to other articles, as the sections of a fishing rod.

The essence of my invention resides in the general form and relative proportions of the reel and inclosing support, which present to the eye an appearance of a comparatively wide construction at the central part thereof, and narrower portions at each end of the same, and the thickness thereof being less than the width, the whole having a very neat and artistic effect.

I claim:

The ornamental design for a reel and inclosing support as shown and described.

MARTIN J. SCHMITT.
